UNITED STATES PATENT OFFICE

ROYE P. GERFEN, OF NEWARK, NEW JERSEY

FOLDABLE BOOTJACK

Application filed July 6, 1932. Serial No. 621,003.

This invention relates to bootjacks and the primary object of this invention is to provide a bootjack which may be folded when not in use and which is of light weight and sturdy construction.

A further object of this invention is to provide a bootjack comprising essentially a front member, a rear member, a pivot pin passing through the adjacent ends of said members and pivotally connecting the same, a spring supported by said pivot and bearing at opposite ends against said members to normally maintain them in extended position for use, and a leg member pivotally supported by the pivot.

A still further object of this invention consists in pivotally mounting the leg member between the front and rear members in such a manner that any force applied to the bootjack will automatically lock the parts from further movement, thereby obviating the danger of breaking any of the parts and automatically restoring the parts to their normal position when the force has been withdrawn.

These and other advantageous objects, which will later appear, are accomplished by the simple and practical construction and arrangement of parts hereinafter described and exhibited in the accompanying drawing, forming part hereof, and in which:

Fig. 1 represents a perspective view of a bootjack made in accordance with my invention,

Fig. 2 represents a top plan view,

Fig. 3 represents a bottom plan view,

Fig. 4 represents a side elevational view, partly in section, taken on line *a*—*a* of Fig. 2, showing the bootjack in position for use,

Fig. 5 represents a similar view, taken on line *b*—*b* of Fig. 2, showing the position assumed by the device when it is inadvertently pushed forward,

Fig. 6 represents a side elevational view of my device in its folded position,

Fig. 7 represents a transverse sectional view taken on line *c*—*c* of Fig. 4, looking in the direction indicated by the arrows, and

Fig. 8 represents an end elevation of the device in its folded position.

Similar letters of reference refer to like parts throughout the specification and drawing.

As shown in the accompanying drawing, the improved bootjack consists, essentially, of the front member 1, provided with a V-shaped opening 2 to receive the heel of the boot to be removed, and the rear member, 3, pivotally connected thereto by the pivot pin 4 passing through apertured knuckles 5—5' integral with the undersurfaces of the inner ends of the members 1 and 3 respectively (see Figs. 3 and 7). The members 1 and 3 are normally maintained extended, in position for use, as shown in Figs. 1 and 4, by the spiral spring 6 surrounding the pivot 4, the legs 6' of the spring bearing against the members 1 and 3, respectively. The device rests, when in use, on the leg 7, which is provided with the apertured arms 8—8 through which the pivot pin 4 passes.

When the device is folded, as shown in Fig. 6, the arms 8—8 of the leg 7 are received in the oppositely disposed, aligned grooves 9—9' on the undersurfaces of the abutting ends of the members 1 and 3, respectively, (see Figs. 2 and 3) and the bar 10, connecting the outer ends of the arms 8—8 is received in opening 2 of the member 1 (see Fig. 8) so that the members 1 and 3 may be snugly folded together with the leg 7 therebetween. The parts are held in this position by any suitable latching means, such, as for instance, the spring clip 11 carried by the member 3 and designed to snap over the member 1, as clearly shown in Figs. 6 and 8.

Upon disengaging the spring clip 11 from the member 1, the latter will be urged, by the action of the spring 6, outward, until the inner ends of the members 1 and 3, respectively, abut, thereby holding the members 1 and 3 respectively in the position shown in Fig. 4. While the member 1 is moving into its extended position the leg 7 will move into the vertical position shown in Fig. 4.

The upper ends of the arms 8—8 of the leg 7 are received in the recesses 12—12 at the inner end of the member 3, (see Figs. 100

1 and 5) and are held therein by the shoulder 14 on the front member 1, which abuts against the upper ends of the arms 8—8 as may be clearly seen in Fig. 1.

5 When the device is in the position indicated in Fig. 4, and is inadvertently moved forward by force applied to it in the direction indicated by the dotted arrow, the device will move forward into the position indicated

10 in Fig. 5, in which position the upper ends of the arms 8 of the legs 7 bear hard against the shoulder 14 of the front member 1 and thereby prevent the bootjack from collapsing any further than shown, and upon the re-

15 releasing of the downward pressure on the member 3, the spring 6 will automatically cause the parts to be returned to their proper position as clearly indicated in Fig. 4.

To lock the device in its folded position, 20 the members 1 and 3 are brought together against the action of the springs 6, causing the member 1 to engage with the hook portion 11' of the spring clip 11. When in this position the leg is located between 25 the members 1 and 3 with the bar 10, which connects the outer ends of the arms 8 of the leg 7, lying in the V-shaped opening 2 of the member 1 as clearly indicated in Fig. 8 of the drawing.

30 To unlock the parts, it is simply necessary to disengage the hook portion 11' of the spring clip 11 from the member 1, which will, due to the action of the spring 6, automatically return the parts to their proper

35 or operative position. The parts of the device are preferably made of any suitable light metal and cut away to save weight and provided with ribs for reenforcing the members, as clearly shown in Fig. 3.

40 The foregoing disclosure is to be regarded as descriptive and illustrative only, and not as restrictive or limitative of the invention, of which obviously an embodiment may be constructed including many modifications 45 without departing from the general scope herein indicated and denoted in the appended claims.

Having thus described my invention, what 50 I claim as new and desire to secure by Letters Patent, is:

55 1. A foldable bootjack comprising a front member, a rear member, a pivot pin passing through the adjacent ends of said members and pivotally connecting the same, a spring supported by said pivot and bearing at opposite ends against said members to normally maintain them in extended position for use, and a leg member carried by the pivot pin.

60 2. A foldable bootjack comprising a front member, a rear member, a pivot pin passing through the adjacent ends of said members and pivotally connecting the same, and a leg member provided with apertured arms through which the pivot pin passes, the outer 65 ends of said arms being connected by a bar.

3. A foldable bootjack comprising a front member, a rear member, a pivot pin passing through the adjacent ends of said members and pivotally connecting the same, and a leg member provided with apertured arms 70 through which the pivot pin passes, the outer ends of said arms being connected by a bar, said front and rear members being provided, at the undersurfaces of their abutting ends, with aligned grooves to receive the arms of the leg members when the device is closed.

4. A foldable bootjack comprising a front member provided with a slot for the reception of the heel of a boot, a rear member, said front and rear members being provided at their inner ends with interfitting complementary knuckles, a pivot pin passing through said knuckles to pivotally connect said members, a spring supported by said pivot pin and bearing at opposite ends 80 against said members to normally maintain them in extended position for use, and a leg member provided with apertured arms through which the pivot pin passes, the outer ends of said arms being connected by a bar, said front and rear members being provided at the undersurfaces of their abutting ends with aligned grooves to receive the arms of the leg members when the device is folded, 85 said bar being adapted to be received in the opening in the front member when the device is folded.

This specification signed this 5th day of July, 1932.
